No. 14, 982

Apr. 29, 1884

GEORGE E NYE

UNITED STATES PATENT OFFICE.

GEORGE E. NYE, OF BRISTOL, PENNSYLVANIA, ASSIGNOR OF ONE-HALF TO EDWARD TREDICK, OF SAME PLACE.

DESIGN FOR HOSIERY.

SPECIFICATION forming part of Design No. 14,982, dated April 29, 1884.

Application filed February 18, 1884. Term of patent 7 years.

To all whom it may concern:

Be it known that I, GEORGE E. NYE, of Bristol, Bucks county, Pennsylvania, have invented a new Design for Hosiery, of which the following is a specification, reference being made to the accompanying photographic representation, forming a part of this specification.

My design embraces, as the main distinguishing feature, a series of raised ribs, a, encircling the calf or body portion of the stocking and of various widths, as shown.

Another distinguishing feature consists in the vertical ribs c, extending the entire length of the stocking.
